Patented Dec. 13, 1921.

UNITED STATES PATENT OFFICE.

JOSIAH FRANCIS JOHNSON, OF EDGEWOOD, PENNSYLVANIA, ASSIGNOR TO WESTINGHOUSE ELECTRIC & MANUFACTURING COMPANY, A CORPORATION OF PENNSYLVANIA.

CONTROL MECHANISM.

1,399,774.

Specification of Letters Patent. Patented Dec. 13, 1921.

Application filed May 31, 1917. Serial No. 171,926.

To all whom it may concern:

Be it known that I, JOSIAH FRANCIS JOHNSON, a citizen of the United States, and a resident of Edgewood, in the county of Allegheny and State of Pennsylvania, have made a new and useful Invention in Control Mechanisms, of which the following is a specification.

This invention relates to control mechanisms and has for an object to produce a new and improved mechanism for controlling the delivery of fluid through at least two different valves.

A further object is to produce a control mechanism which is responsive only to non-synchronous movements of two elements which normally move synchronously.

A further object is to produce a control mechanism in which synchronous movements of a controlling device and one valve have no effect upon a second valve, but in which an independent movement of the controlling device and the first valve will occasion an opening or closing of the second valve.

A further object is to produce a new and improved control mechanism which is especially adapted for controlling the delivery of an auxiliary supply of motive fluid to a low pressure engine or turbine.

A further object is to produce a new and improved control mechanism which will operate independently of the turbine governor in causing high pressure motive fluid to be delivered to a low or mixed pressure turbine when the supply of low pressure motive fluid fails or is insufficient to carry the load.

These and other objects, which will be made apparent throughout the further description of my invention, are attained by means of a mechanism embodying my invention, herein described, and illustrated in the drawing accompanying and forming a part hereof.

The control mechanism illustrated as an embodiment of my invention is well adapted to control the delivery of motive fluid to low pressure turbines. It is common to supply auxiliary high pressure motive fluid to low pressure steam turbines in order to augment or replace the supply of low pressure steam when the available supply of low pressure steam fails or is insufficient to carry the load on the turbine. Mechanisms for controlling the admission of high pressure motive fluid,

hereinafter called steam, to a low pressure turbine, generally require an appreciable reduction in speed of the turbine before the high pressure steam valve is opened. This causes wide variations in the speed of the 60 turbine, which are objectionable in some lines of work and particularly where the turbine is employed in driving an electric generator. By means of my invention high pressure steam may be admitted the instant 65 the supply of low pressure steam becomes insufficient to carry the load, consequently good regulation of the turbine may be maintained. Furthermore, my invention not only enables a more efficient control than was 70 obtainable with other control mechanisms now in use and known to me, but it also enables the use of simpler and more compact apparatus than these other mechanisms.

Figure 1 is a diagrammatic sectional view 75 of a governing apparatus embodying my invention; and Fig. 2 is a diagrammatic view showing the relationship of parts for non-synchronous movements.

As illustrated, the invention is applied to 80 the valve mechanism of a low pressure turbine, the main elements in the mechanism being a governor actuated controlling device 2, a low pressure steam delivery valve B, and a high pressure steam delivery valve C. 85 The low pressure valve B is adapted to deliver low pressure steam to the working passages of a low pressure turbine, (not shown) and the valve C is adapted to deliver high pressure steam to either the same working 90 passages or to a different passage especially adapted to receive high pressure steam.

In this embodiment of my invention, the valve B is of the constant pressure type, having a casing 5 and a valve disk 6 of relatively large size. Steam is delivered to the valve through an inlet port 7 below the valve disk 6. As shown, the upper part of the valve casing 5 is cylindrical in form, and the valve disk 6 is adapted to slide like 100 a piston in this cylindrical portion of the casing. When in its closed position the valve disk 6 cooperates with a valve seat 8, and when open it allows the steam to pass from the lower part of the valve, after entering the inlet port 7, into an annular chamber 9, which surrounds the central portion of the valve immediately above the seat 8, and communicates with a delivery port 10.

In the center of the valve disk 6 and on its 110

upper side I have shown a neck 11, which is enlarged to form a plunger 12 on its upper end. This plunger is adapted to slide in a cylinder 13 formed on top of the valve 5 casing 5 and communicating with the atmosphere by means of a small open port 14 in the cylinder wall above the plunger 12. The hole 14 may be so located and be of such a size that the cylinder 13 will also act as 10 a dash pot to prevent noise or damage due to sudden movements of the valve disk 6. As shown, holes 15 are provided in the valve disk 6 so that the steam pressure is equalized on both sides of the disk, except for the 15 unbalanced pressure on the lower side thereof over an area equal to the cross-sectional area of the plunger 12. This pressure is the only force which tends to open the valve, and it must overcome the weight of the valve 20 disk 6, the neck 11 and the plunger 12, and also the air pressure above the plunger 12 before it can do so. It is evident that the valve will only open when the pressure of the steam entering through the inlet port 7 25 has reached a definite pressure, and for this reason the valve is called a constant pressure valve. If the pressure should decrease below, this the valve would immediately be closed by its own weight and the force of 30 the air pressure above the plunger 12.

I have illustrated a valve stem 16 mounted on the plunger 6 and extending out through the head of the cylinder 13. External pressure on this stem is adapted to move the 35 disk 6 to its seat in opposition to the unbalanced differential pressure of the steam on the lower surface of the disk.

The high pressure valve C is shown as of 40 the familiar balanced puppet type, having a double seated valve disk 17 inclosed by a casing 18. When in the closed position the valve disk 17 is adapted to coöperate with valve seats 19 and 20. Steam is delivered to the valve through an inlet port 21 at the 45 bottom of the casing 18 and then flows to an annular chamber 22 and an outlet port 23 when the valve disk 17 is raised from the valve seats 19 and 20. The valve disk 17 is controlled by means of a stem 24, which extends out through the cover plate 25 of the 50 valve C.

The controlling device A, illustrated as forming a detail of this embodiment of my invention, may be an oil relay controlled piston and cylinder such as is commonly employed in the governing mechanisms of steam turbines. As shown it consists of a cylinder 26 in which a piston 27 operates. Actuating fluid is delivered to the cylinder either above 55 or below the piston 27 by a pilot valve 27^a, which is controlled by a speed governor 27^b. A piston rod 28 is attached to the piston 27 and is shown as carrying a yoke 29 on its upper end. The yoke 29 is connected to a 60 similar yoke 30, below the cylinder 26, by

means of two rods 31 and 32. As shown, the lower yoke 30 is provided with a block 33, which is adapted to engage the outer end of the low pressure valve stem 16 and to thereby control the low pressure valve disk 6. The controlling device A and the low pressure valve B are so located that when the turbine attains the maximum permissible speed the piston 27 and therefore the yoke 30 are in their lowest positions and hold the low 70 pressure valve disk 6 against its seat 8 so as to completely shut off the supply of low pressure steam to the turbine. As the turbine speed decreases the yoke 30 is raised by the piston 27 and if the pressure of the low pressure steam is sufficient to raise the valve disk 6, the disk immediately follows the yoke 30 by reason of the unbalanced differential steam pressure on it, and admits steam to the turbine. The mechanism is so arranged 75 that the yoke 30 has considerably more travel than the low pressure valve disk 6, so that after the valve disk 6 has reached the upper limit of its travel, the block 33 moves away from the stem 16 as the yoke 30 continues 80 its upward movement.

This independent movement of the yoke 30 is adapted to immediately open the high pressure valve C by means of a system of links and levers operatively connecting the 85 yoke 30 and valve stem 16 with the valve C. The system includes a lever 34, which is pivoted to the block 33 and, at its other end, is slidably mounted on a stationary pin 36, which I have shown as mounted on a stationary standard 37. The system also includes a lever or link 35, which is pivoted at one end to the low pressure valve stem 16, and at the other end is connected to the high pressure valve stem 24 by means of a link 100 38. These levers are preferably normally parallel and are illustrated as connected by a short link 39 at a point intermediate their ends. This link may be placed at any intermediate position, depending on the ratio of 105 movement desired between the opposite ends of the rods 34 and 35.

The operation of the apparatus is as follows: If plenty of low pressure steam is available and the turbine is assumed to be 110 running and subjected to an increasing load, the valve 6 is allowed to open because the turbine governor, operating through the device A, moves the yoke 30 upwardly and the steam pressure below the valve disk 6 causes 115 the valve to open in following the yoke. As the load is increased the yoke 30 continues to rise and the valve 6 continues to follow it until the valve reaches the limit of its travel. During this movement the levers 34 and 35 120 remain parallel, the former pivoting on the stationary pin 36 and the latter on the pivot pin between the lever and the link 38.

If the load on the turbine continues to increase after the low pressure valve is fully 125 130

open and consequently after the low pressure steam supply is incapable of supplying sufficient steam to the turbine to maintain the speed at the increasing load, the governor will cause the piston 27 to continue its upward movement and consequently move the block 33 out of contact with the stem 16. This will immediately cause the high pressure valve C to open, since the lever 35 will 10 be caused to fulcrum about its pivotal connection with the stem 16. In this way high pressure steam is supplied to the turbine as soon as the low pressure steam supply is inadequate, and in addition to this the governing 15 function is immediately shifted to the high pressure valve, since it alone moves in response to the governor.

A closing movement of the valve 6, due to a decrease in the low pressure steam supply, 20 and a consequent decrease in the steam pressure below the valve disk will also impart an opening movement to the high pressure valve C, because the downward motion of the valve 6 will cause the lever 35 to fulcrum on the connecting link 39. From this it will be apparent that a failure of the low pressure steam supply acts directly on the high pressure valve without the necessity of the intervention of the governing mechanism, and consequently the time element due 25 to governor lag is eliminated and the steam supply is maintained substantially constant under varying steam pressure conditions and without occasioning appreciable 30 variation in the speed of the turbine. In fact, the adjustment of the valves may be such that a failure of the low pressure steam supply and a consequent increase in the high pressure steam supply will take place without occasioning any variation in the speed 35 of the turbine. It will also be apparent that a building up of the low pressure steam supply, after the turbine is in operation and is receiving high pressure steam from the 40 valve C, will cause the valve B to open and will occasion a corresponding closing of the valve C without the necessary intervention of the governing mechanism.

Assuming that the low pressure valve B 45 is wide open, that the high pressure valve C is partly open, and that the load on the turbine is either gradually or suddenly removed, the governor of the turbine will cause a downward movement of the yoke 30 of the controlling device A. This will first 50 shut off the supply of high pressure steam by moving the levers 34 and 35 into parallelism and thereby closing the valve C, then the block 33 will engage the stem 16 and 55 force the low pressure valve disk downwardly in opposition to the unbalanced steam pressure acting on it and will therefore 60 shut off the supply of low pressure steam so as to maintain the speed of the turbine 65 normal. The variations in speed neces-

sary to actuate the governor are slight and, as there is no lost motion in the controlling mechanism illustrated, no material reduction or increase in speed is necessary in order to bridge the gap between the limit of the 70 operation of one valve and the beginning of the operation of the other valve. In fact, in the apparatus illustrated, there is no gap between the operation of the valves B and C and as soon as one valve has reached the 75 limit of its controlling function the other valve immediately assumes that function. In the illustrated embodiment of my invention the high pressure valve is immediately 80 opened either by failure of the low pressure steam supply or by an increase in load beyond the capacity of the low pressure steam supply.

As long as the block 33 and the stem 16 move in synchronism, the high pressure 85 valve C is unaffected by variations in the position of the governing mechanisms. If the load be light it is understood that the control mechanism A will hold the low pressure valve disk 6 nearly closed and, of 90 course, will allow it to open as the load is increased. Any movements of the controlling device A or the stem 16 which are not in synchronism will immediately actuate the high pressure valve C.

The apparatus which I have illustrated as an embodiment of my invention is unusually simple, reliable and flexible. It effectually prevents the turbine from racing, and provides for good regulation when operating 100 either on low pressure steam, high pressure steam, or a mixture of both. In action it is smooth and continuous, so that no appreciable drop in speed occurs when the change is made from low pressure to high pressure 105 operation or when the load is increased beyond the capacity of the low pressure steam supply.

While I have described and illustrated but one embodiment of my invention, it will be 110 apparent to those skilled in the art that various changes, modifications, additions and omissions may be made in the apparatus illustrated without departing from the spirit and scope of my invention, as set forth by 115 the appended claims.

What I claim is:

1. In a control mechanism, substantially parallel members connected together at an intermediate point by a pivotally mounted 120 connecting member, one end of one member being restrained by a fixed pin so that synchronous movements of the other ends of the members will not affect the substantially parallel relation of the two members, and 125 independent movements of said other ends will cause the members to assume a non-parallel position.

2. In a control mechanism, a system of levers comprising substantially parallel 130

- members connected at an intermediate point by a connecting member, the system being restrained by a stationary pivot at one corner so that a point in the system adjacent to the fixed point is unresponsive to synchronous movements of adjacent points at the other end of the system but is immediately responsive to non-synchronous movements of said points.
10. 3. In a fluid control mechanism, a speed responsive device, a low-pressure fluid controlling valve, responsive to variations in pressure of the fluid controlled and adapted to be contacted by the speed responsive device to impart a closing movement thereto, a high-pressure fluid controlling valve, and means connecting said high-pressure valve to the low-pressure valve and to the speed responsive device so as to allow said high-pressure valve to remain closed as long as the low-pressure valve and the speed responsive device coöperate, and to open said high-pressure valve when the low-pressure valve and the speed responsive device are separated.
15. 4. In combination in a governing apparatus, a governing mechanism, a valve adapted to be moved in only one direction by movement of the governing mechanism, and adapted to be moved in the opposite direction by an independent controlling force, a second valve, a system of links and levers connecting said first and second valves and said governing mechanism so arranged that non-synchronous movement of said first valve and said governing mechanism actuates the second valve.
20. 5. A governing apparatus comprising in combination, a valve chamber having inlet and discharge ports, a valve in the chamber to control communication between the ports and responsive to the pressure of motive fluid at the inlet side to move to open position, a governing mechanism for the valve adapted to have operative and inoperative controlling relation therewith, a second valve, means for connecting the valves with the governing mechanism whereby the second valve is controlled by the governing mechanism and the first valve when the first valve is out of operative controlling relation with the governor.
25. 6. Governing apparatus comprising in combination, a valve, a governor controlled element adapted to engage and control the movements of the valve between open and closed positions, a lever pivoted at one end to the governor controlled element and to a fixed point remote therefrom, a second valve, a link pivoted to the first valve and to the second valve so that synchronous movement of the said element and the first valve does not alter the angular relation of the lever and the link or actuate the second valve, and

the link whereby independent movement of the valve or the said element actuates the second valve.

7. Governing apparatus comprising in combination, a valve, a governor controlled element adapted to engage and control the movements of the valve between open and closed positions, a lever pivoted at one end to the governor controlled element and to a fixed point remote therefrom, a second valve, 70 a link pivoted to the first valve and to the second valve so that synchronous movement of the said element and the first valve does not alter the angular relation of the lever and the link or actuate the second valve, and a pivotal connection between the lever and the link whereby alteration of the angular relation of the lever and the link causes actuation of the second valve.

8. Governing apparatus comprising in combination a governing mechanism, a valve adapted to be controlled thereby and moved synchronously therewith within certain limits of movement of the governing mechanism, a lever pivoted to the governing 85 mechanism at one end and to a fixed point at the other, a second valve, a link pivoted to the first and second valves so that synchronous movement of the first valve and the governing mechanism does not alter the 90 angular relation of the lever and the link, and a pivotal connection between the link and the lever whereby independent movement of the link or lever will actuate the second valve.

9. Governing apparatus comprising in combination, a governing mechanism, a pressure actuated controlling valve for low pressure fluid adapted to be opened in response to the fluid pressure within the valve and 105 controlled by the governing mechanism, the said governing mechanism and the control valve being adapted to operate synchronously between the open and closed positions of the valve and non-synchronously after 110 the valve has opened, a lever pivoted to the governing mechanism and to a fixed point, a high pressure valve, a link pivoted to the high pressure valve and the low pressure valve, so that synchronous movement of the 115 governing mechanism and the low pressure valve does not alter the angular relation of the lever and the link or actuate the high pressure valve, and a pivotal connection between the link and the lever whereby independent movement of the link or the lever will actuate the second valve.

10. In combination in a governing apparatus, a valve responsive to variations in fluid pressure, a governing mechanism for the 125 valve capable only of closing said valve, a second valve, and means for connecting the valves with the governing mechanism whereby the second valve is controlled by the governing mechanism and the first valve 130

when the first valve is out of operative controlling relation with the governor.

11. In combination in a governing apparatus, a valve responsive to variations in fluid pressure, a governing mechanism for the valve capable only of closing said valve, a second valve, and means for connecting the valves with the governing mechanism whereby the second valve may be actuated by either or both the governing mechanism and the first valve.

12. Governing apparatus comprising in combination, a first valve normally biased to closed position and responsive to fluid pressure to open, a governor mechanism, a second valve, and linkage mechanism between the governor mechanism and the valves including a fulcrumed lever between the valves, whereby, when the pressure of fluid for the first valve drops the second valve is opened independently of the governor mechanism.

13. Governing apparatus comprising in combination, a first valve normally biased to closed position and responsive to fluid pressure to open, a governor mechanism, abutment means carried by said valve and the governor mechanism whereby, upon movement in one direction of the governor mechanism, the valve is given a closing movement, a second valve, and linkage mechanism between the governor mechanism and the valves including a fulcrumed lever connected to the valves, whereby, when the pressure of fluid for the first valve drops, the second valve is opened independently of the governor mechanism.

14. In governing apparatus, the combination of a differential low-pressure valve responsive to fluid pressure to open and to a decline in pressure to close, a governor mechanism, a high-pressure valve, linkage

mechanism between the governor mechanism and the valves including a fulcrumed lever pivotally connected to the valves, whereby, when the governor mechanism moves in one direction, the low-pressure valve fully opens and further movement of the governor mechanism operates through the lever fulcruming on the low-pressure valve to open the high-pressure valve.

15. Governing apparatus comprising in combination, a low-pressure motive fluid valve responsive to pressure of motive fluid to move to open position, a governor mechanism, a lever connected at one end to the governor mechanism, a stationary fulcrum for the other end of lever, a high-pressure motive fluid valve, a lever pivotally connected to the valves, and fulcrum means carried by the first lever for supporting the second lever between the valve connections.

16. Governing apparatus comprising in combination, a low-pressure motive fluid valve responsive to pressure of motive fluid to move to open position, a governor mechanism, a lever connected at one end to the governor mechanism, a stationary fulcrum for the other end of lever, a high-pressure motive fluid valve, a lever pivotally connected to the valves, fulcrum means carried by the first lever for supporting the second lever between the valve connections, and abutment means between the first valve and the governor mechanism for moving the low-pressure valve to closing position when the governor mechanism moves in one direction.

In testimony whereof, I have hereunto subscribed my name this 29th day of May, 1917.

JOSIAH FRANCIS JOHNSON.

Witness:

C. W. McGHEE.
